UNITED STATES PATENT OFFICE.

EDWARD W. MONNEUSE, OF WEST NEW BRIGHTON, NEW YORK.

OIL-COCK OPENING AND CLEANING TOOL.

Specification of Letters Patent.

Patented Mar. 4, 1919.

1,296,205.

Application filed July 2, 1917. Serial No. 178,206.

To all whom it may concern:

Be it known that I, EDWARD W. MONNEUSE, a citizen of the United States, residing at West New Brighton, in the county of 5 Richmond and State of New York, have invented certain new and useful Improvements in Oil-Cock Opening and Cleaning Tools, of which the following is a specification.

This invention relates to certain new and 10 useful improvements in an oil-cock opening and cleaning tool and has for its primary object, the provision of a tool of the above stated character which will be of extremely simple construction and operation, as well as 15 highly efficient in use.

Another object of the invention resides in the provision of an oil-cock opening and cleaning tool which will be especially adapted for use in opening and closing oil cocks 20 beneath the body of Ford cars and other motor vehicles and which oil cocks, on account of their location, are exposed and invariably become clogged with mud from the outside and sediment from the inside, and which 25 thereby makes it necessary for the operator to crawl under the car for the purpose of cleaning the oil cock prior to replenishing the motor case with oil.

A further object of the invention resides 30 in the provision of an oil-cock opening and cleaning tool of the above stated character, the embodiment of which will make it possible to open and clean the oil-cock before replenishing the motor case with oil and 35 make it possible for the operator to determine the proper quantity of oil to be applied to the motor case.

A further object of the invention resides 40 in the provision of a tool of the above stated character which will be composed of the minimum number of parts, will be highly efficient in use and may be readily and cheaply manufactured.

A further object of the invention resides 45 in the provision of a tool of the above stated character in which the oil cock cleaning member may be readily secured in position upon the oil-cock opening member or removed, as desired.

With these objects in view and others 50 which may appear as the description proceeds, the invention consists in the novel combination and arrangement of co-operating elements as employed to produce the 55 complete tool as shown in the accompanying drawings, hereinafter more specifically set

forth and pointed out in the appended claims.

In the accompanying drawings forming a part of this application and in which similar 60 reference characters designate corresponding parts throughout the several views,

Figure 1 represents an elevation of the complete tool,

Fig. 2 is a plan view, looking at the working end thereof,

Fig. 3 is a detail sectional view on the plane of line 3—3 of Fig. 1, looking in the direction indicated by the arrows, and,

Fig. 4 is a side elevation of the working 70 end of the tool, taken at right angles to Fig. 1.

Referring more specifically to the drawings, 1 designates the stem of the tool, which has one end bent to form an elongated 75 transverse handle 2, as clearly shown in Fig. 1 of the drawings, while the opposite end is secured through the central portion of the U-shaped member 3, as shown at 4. The opposite or parallel sides 5 of the U- 80 shaped member 3 are suitably spaced to engage the opposite sides of the head formed on the stem of a conventional form of oil-cock (not shown) such as employed as drain cocks beneath the body of Ford automobiles and other motor vehicles. It will also be understood that the stem 1 is of sufficient length to permit engagement of the U-shaped member with the stem of the oil-cock beneath a motor vehicle for the purpose of opening or closing the same without 90 the necessity of crawling beneath the machine. The U-shaped member 3 has a pair of transverse tongues 6 formed therein by providing pairs of parallel slits in the central portion thereof or adjacent the opposite ends thereof, the tongues 6 being pressed upwardly between the sides 5 of the U-shaped member 3, as is clearly shown in the drawings.

The oil-cock cleaning member 7 has its straight portion engaged through the U-shaped member 3 and beneath the tongues 6 thereof, as clearly shown in Figs. 2 and 4, one end 8 of the member 7 being extended 105 to form the oil-cock cleaning portion of the tool. The opposite end of the member 7 is curved upon itself, as shown at 9 and then extended longitudinally beneath the central or body portion of the U-shaped member 3 110 and bent around one side of the stem 1, as shown at 10. The free extremity of the

- member 7 is then bent at a right angle, as shown at 11 and extended upwardly, then bent upon itself, as shown at 12 to form a downwardly directed hook engaged over the 5 extended portion 8 of the member 7, adjacent the U-shaped member 3, thereby securely locking the member 7 upon the U-shaped member 3. By engagement of the portion 9 and hook 12 with the opposite 10 ends of the body of the U-shaped member 3, engagement of the portion 10 with the stem 1 beneath the member 3 and engagement of the main portion of the member 7 under the tongues 6, movement of the member 7 upon 15 the U-shaped member 3 and stem 1 will be positively prevented. It will therefore be seen that the extended portion 8 may be readily employed for cleaning out the oil-cock and the U-shaped member 3 may be 20 employed for opening or closing the oil-cock and the stem 1 and handle 2 will serve to support both parts of the tool and act as the operating means during use of the tool either as an oil-cock opener or oil-cock 25 cleaner.

While the preferred embodiment of the invention has been shown and described, minor changes in the details of construction and arrangement of parts may be resorted to 30 within the scope of the appended claims without departing from the spirit of the invention or sacrificing any of the advantages thereof.

What I claim is:

- 35 1. A tool of the class described comprising a stem, an oil-cock opening member mounted on said stem, an oil-cock cleaning member secured to said oil-cock opening member and having a portion engaging said stem to prevent independent movement of said oil-cock cleaning member, and a handle for said stem.
- 40 2. A tool of the class described comprising a stem, a U-shaped member mounted on

said stem for opening an oil-cock, a cleaning 45 member projecting from said U-shaped member, and a handle for said stem.

3. A tool of the class described comprising a stem, a U-shaped member mounted upon one end of said stem for engagement 50 with an oil-cock to open and close the same, a cleaning member threaded through said U-shaped member, said cleaning member having a clamping portion to prevent movement of said cleaning member with respect 55 to said U-shaped member and said stem, and a handle for said stem.

4. A tool of the class described comprising a stem, an oil-cock opening and closing member carried by said stem, a cleaning 60 member threaded through the first-mentioned member and projecting from one side of the same, means carried by said cleaning member to clamp the same in position, and a handle for said stem.

5. A tool of the class described comprising a stem, a U-shaped member mounted on said stem provided with tongues, an oil-cock cleaning rod threaded through the tongues and having an extended end, the opposite end of said cleaning rod being bent around the U-shaped member and said stem and provided with a hook end for engagement with the extended end of said rod to clamp said rod in position upon said U-shaped member and said stem, the parallel portions of the U-shaped member serving as means to engage an oil-cock for the purpose of opening and closing the same, the extended end of the cleaning rod being 70 75 adapted for use when cleaning the oil-cock, and a handle for said stem.

In testimony whereof I affix my signature in presence of two witnesses.

EDWARD W. MONNEUSE.
